PETROLEUM OIL REFINING

Eric B. Hjerpe, Pittsburgh, and William A. Gruse,
Wilkinsburg, Pa., assignors to Gulf Research
& Development Company, Pittsburgh, Pa., a
corporation of Delaware

No Drawing. Application November 2, 1934,
Serial No. 751,259

1 Claim. (Cl. 196—13)

This invention relates to petroleum oil refining; and it comprises refining methods wherein the oil is admixed with a composite differential solvent composed of ethylene dichloride and another differential solvent of relatively high miscibility temperature characteristics, the mixture is brought to a temperature at which stratification occurs, usually between 100° F. and 0° F., and the oil layer is separated from the solvent layer thus formed, the oil layer being freed of residual solvent to recover an improved refined oil; all as more fully hereinafter set forth and as claimed.

In our copending application, Serial No. 751,256 we have disclosed advantageous processes for refining petroleum oils with ethylene dichloride. The present invention is a modification of and improvement upon the methods there described.

By the present methods, hereinafter more fully described, we obtain substantial and important improvements in the viscosity-index, viscosity-gravity constant, pour point, carbon residue and other properties of the oil.

The viscosity-gravity relationship of oils is a good criterion for judging an oil and is much used as a standard in determining the characteristics of oils. See Hill and Ferris, Industrial and Engineering Chemistry, vol. 17, page 1250 (1925) and Hill and Coats, ibid. vol. 20, page 641 (June 1928). Those authors explain the viscosity-gravity constant and its significance.

The viscosity index (Dean and Davis, Oil and Gas Journal, March 31, 1932, page 92) is also much used in characterizing the viscosity-temperature relations of an oil, a high index indicating a flat viscosity-temperature curve. The differential solvents under discussion have a general effect in lowering the viscosity-gravity constant and raising the viscosity index.

In addition to the improvement in the products obtained, the present processes have certain advantages over the refining of petroleum oils with ethylene dichloride alone. In the methods described in our above acknowledged application Serial No. 751,256, the ethylene dichloride is admixed with the oil at ordinary temperatures and then the mixture is cooled to about 50° F. below the miscibility temperature to effect stratification into an oil layer and a solvent layer. The two layers are separated and the ethylene dichloride is removed from each by distillation. By distilling off the ethylene dichloride, an improved refined paraffinic oil is obtained and also as a separate product, there is obtained a naphthenic oil.

As there stated the miscibility temperature of ethylene dichloride with the usual oils varies between 28° and —15° F.; the exact temperature depending upon the particular oil and other factors.

In the present processes, in lieu of using ethylene dichloride alone, we use a composite differential solvent composed of ethylene dichloride and another differential solvent of relatively high miscibility temperature characteristics, such as liquid sulfur dioxide, methyl cellosolve or furfural. By using such a composite solvent, we obtain modified processes which are advantageous. The presence of the second solvent in conjunction with the ethylene dichloride permits variations and adjustments in various steps of the process. For instance, by controlling the proportions used, the miscibility temperature may be varied so that stratification can be obtained at higher temperatures, not necessitating refrigeration or a saving may be effected in the refrigeration required to cool the mixture.

The solvent extraction of petroleum oil, with various solvents, has been heretofore proposed and practiced. One of the first solvents employed was liquid SO₂. Liquid sulfur dioxide is a highly selective solvent but is of limited utility because of its relatively low solvent power. Thus it will remove from an unrefined stock a small amount of asphaltic and highly naphthenic material leaving a high yield of a slightly improved product. This is not sufficient for commercial purposes, as it is desired to produce a much improved product. In order to effect this it is necessary to remove not only the small proportion of asphaltic and naphthenic material, but also a larger volume of intermediate substances. This sulfur dioxide is unable to effect economically even by the use of extensive amounts of solvent and the resulting improvement of liquid oils is, for most heavy stocks, insufficient.

To overcome that difficulty, it has been proposed to add to the SO₂ a good solvent for the oil to obtain a mixture capable of extracting more material. Good solvents, such as benzol, which are completely miscible with the oil, are used. With the introduction of good solvents, new difficulties arise. Although a better removal of naphthenic bodies is obtained, the loss of good oil (paraffinic oil) is somewhat increased.

As stated in our copending application Serial No. 751,256, ethylene dichloride is a differential solvent for the oil. Our new composite solvents contain two differential solvents each, whereas their nearest analogue, the benzol—SO₂ mixture

comprises a good solvent and a differential solvent. With the new composite solvents, we minimize the loss of good oil with an increase in the solvent power. The addition of the selected differential solvent raises the miscibility temperature. Thus, after adjusting the temperature to obtain stratification, the solvent layer comprises mixed liquids not miscible with the good oil.

By extracting oils with a composite solvent containing ethylene dichloride and another differential solvent of relatively high miscibility temperature characteristics, such as furfural or methyl cellosolve or SO_2 , we obtain a more complete extraction of naphthenic bodies, a better selectivity, a reduction in the loss of good oil and a higher yield of superior refined oil. All of these advantages cannot be obtained in any one of the prior art processes.

Because of the wide diversity of lubricating oils stocks to be improved, solvents of widely different characteristics are often necessary. This variation may be obtained by changing solvents, but such a method is undesirable because usually each type of solvent requires a different plant installation for its use, and much additional investment would be required. Thus nitrobenzene, furfural, phenol and other solvents may each give good results on certain stocks and not on others; but it is not practical to shift quickly from one solvent to another. By the use of mixtures of ethylene dichloride with sulfur dioxide it is possible to obtain wide variations in the characteristics of the composite solvent in hand without any change in plant requirements or any additional investment. Thus where desired, light distillates may be treated with sulfur dioxide alone; light naphthenic lubricating distillates can be processed with mixtures comprising as little as 10 per cent ethylene dichloride and 90 per cent sulfur dioxide, while heavy paraffinic stocks may require mixtures with sulfur dioxide in the order of 75 per cent of ethylene dichloride or higher for certain types of oils. Extraction at low temperatures is advantageous, and the above flexibility as to composition of solvents permits the use of rather wide temperature ranges without impairing separation efficiency.

Similar advantages may be obtained by the mixture of ethylene dichloride with furfural or methyl cellosolve in appropriate proportions.

In practicing the present invention a suitable amount of the composite solvent is brought into contact with the oil to be refined. This may be at a temperature above that at which the oil and solvent become completely miscible, with subsequent cooling, but in general it is at the temperature desired for the extraction. This may be between say 100° F. and say 0° F. Thus, for most wax-bearing stocks, the extraction temperature is advantageously 75° F., while for dewaxed or wax-free oils, it is conveniently 25° F. or lower. There is a definite advantage in yield by working at low temperatures. The mixed oil and solvent is held at this temperature long enough to permit clean stratification, the layers are separated and the extraction repeated on the upper or oil layer, as often as desired, say 3 or 4 times. Alternatively the extraction may be a continuous one, the oil and solvent being pumped countercurrently in the proper volume ratio and at the proper temperature through one or more mixing and settling chambers.

To recover the improved refined oil, the oil layer is freed of residual solvent, usually by simple

distillation. The distillation may be controlled to recover each of the solvents for re-use in the process.

Likewise, the solvent is recovered from the solvent layer for re-use in the process. After separating the solvent, there is obtained a useful naphthenic oil.

In such processes, usually between two and six volumes of composite solvent for one volume of oil are used. Composite differential solvents containing ethylene dichloride and SO_2 in ratios between 10:90 and 75:25 are advantageous. For most oil stocks, a ratio of 30:70 is satisfactory. As the ratio is varied, the miscibility temperature changes; the miscibility temperature is raised as the amount of SO_2 is increased. Analogous limits apply for mixtures of ethylene dichloride with furfural and methyl cellosolve. For instance mixtures of ethylene dichloride with methyl cellosolve or furfural in the proportions of 20:80 to 80:20 can be used successfully by making suitable adjustments of extraction temperatures.

In a way, the ratios, the volume of solvent and the stratification temperatures employed are somewhat dependent upon whether dewaxing precedes or is subsequent to the solvent extraction.

From the above description, it is believed persons skilled in the art will understand the various applications and modifications of the generic invention. A further illustration of the generic invention is the following typical embodiment.

Example 1.

100 parts of overhead cylinder stock from Oklahoma crude is mixed at a temperature of 75° F. with 40 parts of ethylene dichloride and 60 parts of SO_2 . The mixture is agitated and maintained at that temperature for half an hour until clean stratification into an oil layer and a solvent layer is obtained. The lower solvent layer is withdrawn and the oil layer is extracted three more times with a like volume of said composite solvent.

The separated oil layer is then freed of solvent by distillation to obtain an improved refined oil. There are obtained 60.8 parts by weight of a refined oil having the following properties, as compared with the original:

	Original	Refined oil
Specific gravity	0.927	0.8944
Viscosity at 210° seconds Saybolt	130	94
Viscosity index	75	55
Viscosity gravity constant	0.852	0.815
Carbon residue, per cent	2.08	0.43

The ethylene dichloride and SO_2 removed from the good oil by distillation may be recovered for re-use in the process. Likewise, the solvent may be recovered from the solvent layer for re-use in the process. Thirty-nine and two-tenths parts of useful naphthenic oil is obtained when the solvent is so removed. The specific gravity of this naphthenic oil is 0.988 as compared with 0.927 on the original oil.

As stated ante in this specification, the oil may be previously or subsequently dewaxed in any appropriate manner as has been indicated.

In lieu of the composite solvent used in Example 1, mixtures of ethylene dichloride and SO_2 in other ratios may be used. Likewise, the separation of the oil layer and solvent layer may be effected at other temperatures so long as the

temperature is sufficient to produce a clean complete stratification. Such points are illustrated by Example 2.

Example 2

5 100 parts of a naphthenic lubricating distillate from Gulf Coastal crude having a viscosity of 71 Saybolt at 210° F. is extracted at 50° F. with four successive portions of 100 parts each of a mixture comprising 30 per cent ethylene dichloride and 70 per cent liquid sulfur dioxide. This 10 operation is performed under the vapor pressure of the mixture. The solvent is removed from each layer by distillation and a refined oil product amounting to 65.3 parts of the charge is removed. The improvement obtained is easily seen 15 from the following properties of the original and refined oils.

	Original	Refined oil
Specific gravity	0.936	0.909
Viscosity at 210° Saybolt	71	68
Viscosity index	4	60
Viscosity gravity constant	0.877	0.842

Example 3

20 100 parts of overhead cylinder stock from Oklahoma crude are extracted with 200 parts of a mixture of ethylene dichloride with methyl cellosolve in the ratio 70:30 at 32° F. The raffinate layer so obtained is separated from the solvent layer and then twice extracted with 100 parts of the same solvent mixture in the same way. The 25 solvents were removed from the final raffinate layer by distillation. The yield of refined oil was 52 parts by weight. The comparison of the original and the refined oil is as follows:

	Original	Refined oil
Specific gravity	0.927	0.8944
Viscosity Saybolt 210° F.	180	93
Viscosity gravity constant	0.853	0.815
Carbon residue	2.05	0.65

Example 4

100 parts of overhead cylinder stock from Oklahoma crude are extracted with 100 parts of a mixture of ethylene dichloride and furfural in the ratio of 50:50 at 75° F. The raffinate layer is separated from the solvent layer and the extraction is repeated three times in the same manner. The solvents are removed from the final raffinate by distillation. A yield of 63.9 parts by weight of refined oil is obtained. The comparison of the original and refined oil is as follows:

	Original	Refined oil
Specific gravity	0.927	0.8976
Viscosity Saybolt 210° F.	130	96
Viscosity gravity constant	0.853	0.819
Carbon residue	2.05	0.50

20 As indicated earlier in this specification, suitable heat exchange may be effected between the cool liquids obtained in these processes and the hot liquids and vapors, to economize the heat and refrigeration required.

25 What we claim is:

30 The method of decreasing the viscosity-gravity constant of a petroleum lubricating oil, which comprises extracting the oil at a temperature between 0° and 100° F. with a composite solvent comprising a mixture of ethylene dichloride and liquid sulfur dioxide, in which the ratio of ethylene dichloride to sulfur dioxide is between 10:90 and 75:25, the miscibility temperature characteristic of the composite solvent being higher than that of ethylene dichloride alone, and finally separating the solvent, together with constituents extracted from the oil, from the extracted oil.
